SWASH PLATE ROTARY ENGINE

Filed Feb. 26, 1930

Fig. 1.

UNITED STATES PATENT OFFICE

JOHN FREDERICK NEVINSON CRAIG, OF BROXBOURNE, ENGLAND

SWASH-PLATE ROTARY ENGINE

Application filed February 26, 1930, Serial No. 431,556, and in Great Britain January 17, 1929.

This invention is for improvements in or relating to swash-plate rotary engines, the term including pumps, blowers, meters, motors and the like.

Engines of this kind take various forms. They essentially, however, comprise a plurality of pistons arranged in a ring with their axes parallel. The pistons are operated in their cylinders by the cam action upon them of a plate (termed the swash-plate) which intercepts the axes of the several pistons at an angle. In some engines the swash-plate rotates in relation to the pistons, the cylinders being stationary. In others the cylinders rotate and the swash-plate is stationary. In either case it is a question of cam action of the swash-plate upon the pistons, and, as will be appreciated, the form of bearing employed, as between the pistons and swash-plate, is of first importance, especially in the case of engines which have to operate against high pressure or at high speeds.

In certain known forms of swash-plate engines the pistons have engaged the rotating swash-plate through the medium of connecting rods ball-jointed at the top of a thrust-race interposed between them and the swash-plate. This construction, however, is expensive to manufacture and it calls for much lubrication. Moreover, the permissible load at high speeds is not sufficiently high for many purposes.

In other known forms of swash-plate engines, the pistons themselves engage the swash-plate, bearing at their outer ends upon a thrust-race, which in turn bears upon the swash-plate through the medium of ball- or rolling-bearings, the thrust-race being interposed in a plane parallel to the swash-plate and between it and the piston ends. The pistons are held up to the thrust-race by a retaining member (e. g. a spider) pivoted between the pistons and extending radially from its pivot into engagement with each of them. It is to engines of this particular type

(hereinafter referred to as the type described) that the present invention relates.

According to the invention of my prior United States application for Letters Patent No. 274,888, each piston in a swash-plate rotary engine of the type described engages the thrust-race through the medium of a ball-bearing mounted in the end of the piston and comprising a spherical ball rollable within a spherical cup-shaped ball-race upon a ring of balls freely rollable in the race under the ball.

With this form of bearing, friction as between the pistons and the swash-plate is very greatly reduced as compared with other forms of bearing. In this connection, it should be pointed out that as the cylinder block and thrust-race rotate in relation to the fixed swash-plate, or according to the alternative construction of engine, as the swash-plate rotates in relation to the stationary cylinder block, the several points of contact of the pistons with the thrust-race trace out small circular paths on the face of the race, but since the spherical ball bears with rolling contact upon the face of the race and also upon the ball-bearings under it, and as the latter in turn are freely rollable in the spherical race in which they are mounted, the tracing out of said circular paths does not involve rubbing contact as between the pistons and the thrust-race.

The present invention comprises an improvement in or modification of the invention of my said prior application which consists in providing, in respect of each piston, in rotary swash-plate engines of the type described, a ball-bearing interposed between the swash-plate thrust-race and the piston and comprising a ball-race the bearing-surface of which is spherical, which ball-race is carried on the thrust-race, an intermediate bearing-element (e. g. a spherical ball) interposed between said ball-race and the piston and having at one side a spherical bearing-

surface opposed to and concentric with the ball-race, balls working between the two bearing-surfaces and two further opposed bearing-surfaces, one on the other side of the intermediate bearing-element and the other on the piston, of such shape that the relative movement of the two surfaces is that of rolling contact.

According to a further feature of the invention, that surface of the bearing-element which is opposed to the bearing-surface on the piston is spherical and concentric with the other bearing-surface of the bearing-element, and the bearing-surface on the piston is a plane surface perpendicular to the axis of the piston. This particular construction ensures that the thrust transmitted to the piston from the swash-plate is directed along a line which is co-incident with, or parallel to, the axis of the piston. A lateral component of this thrust is thereby avoided, and, in consequence, friction on the cylinder walls from this cause is eliminated.

A preferred construction is one in which the intermediate bearing-element is constituted by a plain spherical ball cradled at one side in a ring of ball-bearings working in a concave spherical ball-race carried by the swash-plate thrust-race, and bearing at the other side upon a plane surface provided on the piston-end in a plane perpendicular to the axis of the piston. It is to be understood, however, that the invention is not limited to this particular form of parts. For example, the bearing-element could take the form of a bowl having concentric spherical internal and external surfaces, in which event the external surface of the bowl would bear upon a plane bearing-surface on the piston-end, and the internal surface would roll upon a ring of ball-bearings interposed between it and a convex spherical ball-race carried on the thrust-race and concentric with the internal and external spherical surfaces of the bearing-element.

The invention is illustrated by way of example in the accompanying drawings of which—

Figure 1 is a vertical section through the end of one of the pistons of a swash-plate engine embodying the improved bearing of the invention as between the piston-end and the swash-plate of the engine, and

Figure 2 is a second vertical section showing an alternative form of the bearing.

Like reference characters indicate like parts in the two figures on the drawings.

The general design of the engine is similar to that of the engine described in the parent application No. 274,888. Briefly, the engine comprises a rotary cylinder-block in which there are six cylinders equally spaced in a circle which is concentric with the axis of the cylinder-block, the several cylinders being parallel to one another and to the axis of

rotation of the cylinder-block. In each cylinder is a piston the outer end of which bears against the rotating race of an inclined thrust-block. The said race is rotatable in a plane which is inclined to the direction of the axes of the pistons, and consequently also to the axis of rotation of the cylinder-block. The piston-ends are held up to the rotating race by means of a spider, the centre of which is universally jointed so as to be capable of rotating with the pistons and cylinder block, the ends of the arms of the spider projecting into the interior of the piston-ends and at their extremities engaging bearing projections on the underside of the piston-ends. As the cylinder-block rotates the pistons travel round with it and being held up to the inclined thrust-race are caused to reciprocate in their cylinders.

Referring now to the drawings accompanying this specification, the cylinder-block is marked 1, one of the pistons therein 2, the rotating inclined thrust-race 3, and one arm of the piston-retaining spider 4.

The thrust-race 3 bears upon a fixed race 5 secured to the stationary framework 6 of the engine.

The improved bearing of the present invention comprises a spherical ball 7 bearing with point-contact upon a plane surface 8 of a hardened steel plug 9 let into the outer end of a flanged sleeve 10 fitted in the outer extremity 11 of the piston. The ball 7 bears at the opposite side (the top) upon a ring of balls 12 freely rollable in a spherical concave ball-race 13 fixed to the face of the rotating thrust-race 3.

The centre of curvature of the spherical race 13 is co-incident with the centre of the spherical ball 7. Consequently, as will be appreciated, the piston-end bears against the rotating race 13 at all times with point-contact; the ball 7 rolls with point-contact on the plane surface 8 as the piston reciprocates and travels round with the cylinder-block and rotating race 3, and it also rolls with point-contact upon the spherical surface of the balls 12 which in turn roll with point-contact upon the spherical surface of the race 13.

Preferably, the arm 4 of the piston-retaining spider engages the piston through the medium of a yielding bearing adapted to take into account the slight variation which occurs, as the cylinder-block and pistons rotate, in the distance between the extremity of the spider where it engages and the interior of the piston-end and the centre of ball 7, the object being of course to insure that the spider arm shall at all times bear upon the piston end and hold the latter properly in place against the bearing-ball 7.

To this end there may be provided, as shown, the spring-pressed plunger 14 slideable in the sleeve 10 and spring-controlled by

a compression-spring 15 towards the extremity of the spider arm 4, bearing, on the underside of its head 16, upon said spider arm extremity through the medium of a bearing-ball 17.

Figure 2 shows a modification in which the bearing ball 7 is substituted by a bowl-shaped bearing element 18. The bearing element 18 is formed with two spherical surfaces 19, 20 which are concentric with one another and with a hemi-spherical concave ball-race 21 fixed to the rotating thrust-race 3. As in the case of the ball 7, the bearing element rolls with point-contact on the plane surface 8 provided on the extremity of the piston and also rolls with point-contact upon the spherical surfaces of a ring of balls 12 which in turn are freely rollable with point-contact upon the spherical surface of the race 21 in the space between said race and the surface 20 of the bearing-element.

If desired a bearing such as has been described as between the piston-end and the swash-plate thrust-race 3, may be provided also as between the end of the spider arm 4 and the interior of the piston-end. Generally, however, the load taken at this point is considerably smaller than the working load at the point of bearing as between the piston and the swash-plate thrust-race. Consequently, where circumstances and requirements permit, the construction is preferably one, as shown, in which the spider arms simply engage the piston-ends with plain rubbing contact.

It is to be understood that the invention includes, in a rotary swash-plate engine of the type hereinbefore referred to, the provision, in respect of each piston, of two parallel plane bearing-surfaces disposed in the end of the piston in planes which are perpendicular to the direction of reciprocation of the piston, of which bearing-surfaces one is yieldingly mounted in the piston-end to move parallel to itself longitudinally of the piston and the other is unyieldingly mounted, and two spherical bearing-surfaces carried one on the swash-plate thrust-race and the other on the piston-retaining-member and bearing respectively on the two parallel plane bearing-surfaces aforesaid.

Further, in a modified form of the invention, the bowl-shaped spherical bearing-element referred to above may be mounted upon the piston-end so that its external surface rolls upon the rotatable thrust-race of the swash-plate, the said race being formed accordingly with a plane-bearing-surface parallel to the thrust-race and the spherical ball being rollably mounted through the medium of a ring of ball-bearings upon a convex ball-race carried in the piston-end. This ball-race may, if desired, take the form of a sphere resting in a hardened steel cup let into the piston-end. In this form of the invention,

moreover, the hardened steel cup may be yieldingly mounted in the piston-end so as to be movable longitudinally of the piston, in which event the piston-retaining-member would bear upon a fixed spherical bearing-surface in the interior of the piston-end, or alternatively, the hardened steel cup can be fixed relatively to the piston-end and the spherical bearing-surface which is engaged by the retaining member may be yieldingly mounted to move in the direction of the length of the piston.

I claim:—

1. In a multi-cylinder rotary engine having a plurality of parallel cylinders, and having pistons reciprocating in said cylinders, the combination with a swash-plate inclined to the axes of the cylinders, of thrust-bearing means interposed between said pistons and said swash-plate, means extending into said pistons for retaining said pistons, thrust-bearing means and swash plate in substantial engagement, and yielding means interposed between said retaining means and each of said pistons and exerting thrust therebetween to compensate for variations in the distance between said retaining means and said swash-plate.

2. In a multi-cylinder rotary engine having a plurality of parallel cylinders, and having pistons reciprocating in said cylinders, the combination with a swash-plate inclined to the axes of the cylinders, of thrust-bearing means interposed between said pistons and said swash-plate, means for retaining said pistons, thrust-bearing means and swash-plate in substantial engagement, and yielding means carried by each of said pistons and engaging said retaining means and exerting thrust between said pistons and said retaining means to compensate for variations in the distance between said retaining means and said swash-plate.

3. In a multi-cylinder rotary engine having a plurality of parallel cylinders, and having pistons reciprocating in said cylinders, the combination with a swash-plate inclined to the axes of the cylinders, of thrust-bearing means interposed between said pistons and said swash-plate, means for retaining said pistons, thrust-bearing means and swash-plate in substantial engagement, and a spring pressed plunger slidably carried in each of said pistons and engaging said retaining means and exerting thrust between said pistons and said retaining means to compensate for variations in the distance between said retaining means and said swash-plate.

4. In a multi-cylinder rotary engine having a plurality of parallel cylinders, and having pistons reciprocating in said cylinders, the combination with a swash-plate inclined to the axes of the cylinders, of thrust-bearing means in line with each piston and associated with said swash-plate, a sleeve in-

serted in one end of each of said pistons,
said sleeves having flat surfaces for engag-
ing said thrust-bearing means, a spring
pressed element slidably supported in each
of said sleeves, and a member for retaining
said pistons and associated sleeves against
said thrust-bearing means, said member en-
gaging said spring pressed elements.

In testimony whereof I affix my signature.

JOHN FREDERICK NEVINSON CRAIG.
